CLAIM

The ornamental design for a saw tooth picture hanger or similar article, as shown and described.

DESCRIPTION

FIG. 1 is a front elevational view of a saw tooth picture hanger or similar article showing my new design;

FIG. 2 is a rear elevational view thereof;

FIGS. 3 and 4 are respectively top and bottom plan views thereof;

FIG. 5 is an end elevational view thereof, the opposite end elevational view being a substantially mirror image thereof;

FIG. 6 is a front perspective view of the hanger shown in FIG. 1 taken from above and to one side; and

FIG. 7 is a rear perspective view of the hanger shown in FIG. 2 taken from below and to one side.

FIG. 1.

FIG. 2.

FIG. 3.

FIG. 4.

FIG. 5.

FIG. 6.

FIG. 7.
